UNITED STATES PATENT OFFICE.

OLOF N. TEVANDER, OF CHICAGO, ILLINOIS, ASSIGNOR TO STANDARD CAP & SEAL CORPORATION, OF CHICAGO, ILLINOIS, A CORPORATION OF VIRGINIA.

BOTTLE CLOSURE AND METHOD OF PRODUCING THE SAME.

Application filed March 3, 1927. Serial No. 172,402.

My invention relates to bottles and their closures and to a method of applying the closures to the bottles.

Generally speaking, the bottle closure of my invention is produced by placing a skirted cap over the mouth of the bottle and about the bottle neck, contracting a ring about the cap skirt by relatively moving adjacent portions thereof oppositely and circumferentially, and holding said ring portions in assembly with the cap skirt and in ring contracting relation by means of sealing wax or other cement which is directly applied to said adjacent ring portions and to the portion of the cap skirt underlying these ring portions.

In the preferred embodiment of the invention, the ring is formed of string which is wrapped around the bottle neck and whose adjacent portions that are moved oppositely and circumferentially of the bottle are in lapping relation within a single patch of sealing wax or other cement which thus serves to hold the ring under tension to preserve the ring in tight engagement with the cap skirt and thereby hold the cap skirt in tight engagement with the bottle neck. The bottle neck is externally enlarged at the mouth of the bottle, the ring being placed below the enlargement of the bottle neck so that the cap can not be removed since the ring is cemented to the cap skirt and because of the cementing of the ring to the cap skirt, the ring can not be moved downwardly from the cap skirt into a cap releasing position.

The invention will be more fully explained in connection with the accompanying drawing in which Fig. 1 is a side view of a milk bottle and a cap applied thereto in accordance with my invention; Fig. 2 is a cross sectional view on line 2-2 of Fig. 1, on a larger scale; and Fig. 3 is a longitudinal sectional view of the upper portion of the bottle.

The bottle 1 illustrated is one which is commonly employed for containing milk or cream. It has an external enlargement or surrounding bead 2 at its mouth. It is customary to provide an annular seat 3 at the mouth of the bottle for receiving a closure disc 4, this closure disc, however, forming no essential part of my invention. A cap 5, preferably of paper, is placed over the mouth of the bottle and over the closure disc 4, this

cap having a skirt 6 integral therewith and which is tightly embraced by a ring 7, which ring, by reason of its tight engagement with the cap skirt, forces the cap skirt into tight engagement with the bottle neck. The ring, which is located below the bottle enlargement 2, is preferably non-metallic, being desirably made of fibrous string. The adjacent portions 7' of the ring are drawn oppositely and circumferentially to contract the ring tightly into engagement with the skirt of the bottle cap to apply this cap skirt tightly against the bottle neck. These ring portions are desirably the ends of a section of string which is long enough to be encompassed about the bottle neck in the manner desired.

Sealing wax or other cement, preferably a single patch 8 thereof, is applied directly to the lapping ring portions 7' and to the skirt of the cap. If the cement be sealing wax, it is applied in hot or fluxed condition and is allowed to cool and harden while the lapping ring portions 7' are drawn upon tightly oppositely and circumferentially to hold the ring tightly contracted about the cap skirt so that, after cooling and hardening, the wax serves to hold said ring portions and preferably the entire ring under tension or in contracted condition to maintain the cap in firm assembly with the bottle. The ring being below the enlargement 2 of the bottle, and the single patch of sealing wax which is thus directly applied to the cap skirt and the adjacent ring portions being also below said enlargement, the cap can not be removed from the bottle without detection, nor can the ring be moved downwardly to a cap releasing position. For further protection, the single patch of sealing wax may have impressed thereon a mark identifying the source of the milk.

Having thus described my invention, I claim:

1. The method of sealing a bottle which consists in placing a skirted cap over the mouth of the bottle and about the bottle neck; contracting a ring about the cap skirt by relatively moving adjacent portions thereof oppositely and circumferentially into lapping relation; placing a patch of hot sealing wax directly upon said ring portions and directly upon the portion of the cap skirt at these ring portions; and holding the ring portions in ring contracting relation while

the patch of sealing wax cools to enable it to hold said ring portions in ring contracting relation.

2. The method of sealing a bottle which 5 consists in placing a skirted cap over the mouth of the bottle and about the bottle neck; contracting a ring about the cap skirt by relatively moving adjacent portions thereof oppositely and circumferentially; placing 10 a patch of hot sealing wax directly upon said ring portions and directly upon the portion of the cap skirt at these ring portions; and holding the ring portions in ring contracting relation while the patch of sealing wax 15 cools to enable it to hold said ring portions in ring contracting relation.

3. The method of sealing a bottle which consists in placing a skirted cap over the mouth of the bottle and about the bottle 20 neck; contracting a ring about the cap skirt by relatively moving adjacent portions thereof oppositely and circumferentially into lapping relation; placing a patch of cement directly upon said ring portions and directly 25 upon the portion of the cap skirt at these ring portions; and holding the ring portions in ring contracting relation while the patch of cement hardens to enable it to hold said ring portions in ring contracting relation.

30 4. The method of sealing a bottle which consists in placing a skirted cap over the mouth of the bottle and about the bottle neck; contracting a ring about the cap skirt by relatively moving adjacent portions 35 thereof oppositely and circumferentially; placing a patch of cement directly upon said ring portions and directly upon the portion of the cap skirt at these ring portions; and holding the ring portions in ring contracting 40 relation while the patch of cement hardens to enable it to hold said ring portions in ring contracting relation.

5. A bottle whose neck is externally enlarged at the mouth of the bottle, in combination with a skirted cap placed over the mouth of the bottle and about the bottle neck; a skirt contracting ring about the cap skirt below the enlargement at the mouth of the bottle, said ring having adjacent portions 50 drawn oppositely and circumferentially and in lapping relation to hold the ring contracted; and a patch of cement placed directly upon said ring portions and directly upon the portion of the cap skirt at these 55 ring portions and serving to hold these ring portions in ring contracting relation.

6. A bottle whose neck is externally enlarged at the mouth of the bottle, in combination with a skirted cap placed over the mouth of the bottle and about the bottle neck; a skirt contracting ring about the cap skirt below the enlargement at the mouth of the bottle, said ring having adjacent portions drawn oppositely and circumferentially 60 to hold the ring contracted; and a patch 65

of cement placed directly upon said ring portions and directly upon the portion of the cap skirt at these ring portions and serving to hold these ring portions in ring contracting relation.

7. The method of sealing a bottle which 70 consists in placing a skirted cap over the mouth of the bottle and about the bottle neck; contracting a ring about the cap skirt by relatively moving adjacent portions thereof oppositely and circumferentially; and directly applying cement to said ring portions and cap skirt.

8. The method of sealing a bottle which 80 consists in placing a skirted cap over the mouth of the bottle and about the bottle neck; contracting a ring about the cap skirt by relatively moving adjacent portions thereof oppositely and circumferentially; directly applying cement to said ring portions and cap skirt; and holding each of said ring portions under tension by its attachment to the cap skirt.

9. A bottle whose neck is externally enlarged at the mouth of the bottle, in combination with a skirted cap placed over the mouth of the bottle and about the bottle neck; a skirt contracting ring placed tightly about the cap skirt; and cement directly applied to adjacent portions of the ring and to the cap skirt adjacent said ring portions and taking part in holding said ring portions under tension, said ring being below the enlargement at the mouth of the bottle.

10. A bottle whose neck is externally enlarged at the mouth of the bottle, in combination with a skirted cap placed over the mouth of the bottle and about the bottle neck; a skirt contracting ring placed tightly about the cap skirt and having one portion secured to the cap skirt; and cement directly applied to an adjacent portion of the ring and to a portion of the cap skirt adjacent this ring portion and taking part in holding this ring portion under tension, said ring being below the enlargement at the mouth of the bottle.

11. A bottle whose neck is externally enlarged at the mouth of the bottle, in combination with a skirted cap placed over the mouth of the bottle and about the bottle neck; a skirt contracting ring placed tightly about the cap skirt; and a patch of cement directly applied upon adjacent portions of the ring and to the cap skirt adjacent said ring portions, said ring being below the enlargement at the mouth of the bottle.

12. A bottle whose neck is externally enlarged at the mouth of the bottle, in combination with a skirted cap placed over the mouth of the bottle and about the bottle neck; a skirt contracting ring placed tightly about the cap skirt and having one portion secured to the cap skirt; and a patch of cement directly applied upon an adjacent

portion of the ring and to a portion of the cap skirt adjacent this ring portion, said ring being below the enlargement at the mouth of the bottle.

5 13. A bottle whose neck is externally enlarged at the mouth of the bottle, in combination with a skirted cap placed over the mouth of the bottle and about the bottle

neck; a skirt contracting ring placed tightly about the cap skirt; and a patch of cement 10 directly applied upon the ring and the cap skirt, said ring being below the enlargement at the mouth of the bottle.

In witness whereof, I hereunto subscribe my name.

OLOF N. TEVANDER.
